UNITED STATES PATENT OFFICE.

CHARLES W. ANDREWS AND FRANK H. ANDREWS, OF NEW HAVEN, CONNECTICUT, ASSIGNORS TO THE MALLORY WHEELER COMPANY, OF SAME PLACE.

DESIGN FOR THE ORNAMENTATION OF BUILDERS' HARDWARE.

SPECIFICATION forming part of Design No. 19,533, dated December 31, 1889.

Application filed October 7, 1889. Serial No. 326,287. Term of patent 7 years.

To all whom it may concern:

Be it known that we, CHARLES W. ANDREWS and FRANK H. ANDREWS, of New Haven, in the county of New Haven and State of Connecticut, have invented a new Design for the Ornamentation of Builders' Hardware; and we do hereby declare the following, when taken in connection with the accompanying drawings and the letters of reference marked thereon, to be a full, clear, and exact description of the same, and which said drawings constitute part of this specification, and represent, in—

Figure 1, a face view of an escutcheon embodying the design, only a portion of which is completed; Fig. 2, a similar view of a door-knob embodying the design; Fig. 3, a sectional view of the escutcheon, taken on line *x x* of Fig. 1.

This invention relates to a design for the ornamentation of that class of articles commonly called "builders hardware"—such as escutcheons, butts, lock-fronts, knobs, bell-pulls, and other articles of like character—the invention consisting in the representation of alternate elevations and depressions arranged in waved parallel lines to give the appearance of agitated water and inclosed in a border.

In representing the design we have shown its application to an escutcheon and to a door-knob; but it may be applied, as above stated, to builders' hardware generally. The main portions of the surfaces of these articles represent a watered groundwork, the watered effect being secured by means of alternate elevations and depressions, which are arranged in waved parallel lines. These elevations and depressions are arranged in groups disposed counter to each other, as

shown in the drawings, so as to secure the effect of counter-currents of water, whereby the design is enlivened. A flat marginal raised band incloses the ornamentation as a border.

Any desired ornamentation may be placed in relief upon the described watered groundwork. As herein shown, the ornamentation in relief consists of Arabic characters, which, however, may be replaced by any other desired form of ornamentation. These characters, or any ornamentation which may replace them, form, however, no part of this design, the essential and characteristic feature whereof is the watered groundwork.

It will be understood that the shape of the article and the nature of its use may, to some extent, change the general arrangement of the watered groundwork; but the illustrations which we have made will enable others skilled in the art to which this design relates to apply the design to the surfaces of various articles which go to make up the class to which this design particularly belongs.

We claim—

The herein-described design for the ornamentation of hardware, consisting in the representation of alternate elevations and depressions arranged in waved parallel lines to give the appearance of agitated water, and the representation of a raised marginal band inclosing the ornamentation as a border, substantially as described, and shown in the accompanying illustration.

CHARLES W. ANDREWS.
FRANK H. ANDREWS.
